(74) Attorney, Agent, or Firm — STEPTOE LLP

(57)

CLAIM

The ornamental design for a container with lid as shown and described.

DESCRIPTION

FIG. 1 is an isometric perspective view of a container with lid illustrating my new design;

FIG. 2 is a front elevation view thereof.

FIG. 3 is a rear elevation view thereof.

FIG. 4 is left side elevation view thereof.

FIG. 5 is right side elevation view thereof.

FIG. 6 is a top plan view thereof; and,

FIG. 7 is a bottom plan view thereof.
